TRACK SHOE WITH CUSHIONED HEEL-
RECEIVING POCKET

George H. Gillis, Fitchburg, Mass.

Application November 4, 1949, Serial No. 125,611

2 Claims. (Cl. 36—25)

1

This invention relates to athletic shoes and more particularly to shoes constructed to meet the requirements of track athletes. Shoes for this service are subjected at times to heavy pressure at the heel portion, and laterally extended fasteners, such as stitches, or the like, at this portion of the shoe, which present less yielding portions than adjacent shoe parts are liable to cause discomfort to the wearer.

It is an object of the present invention, therefore, to provide a shoe devoid of such less yielding portions where the heavy pressure is exerted at the heel, and further to provide substantial cushioning means for the heel which will distribute the pressure over an extended area and will absorb sudden and severe shocks. To these ends the outersole of the shoe constructed in accordance with this invention is continued rearwardly beyond the sole portion of the shoe up the back of the foot in a continuous smooth curve, and inwardly of this curve there is positioned a cushioning pad of yielding material such as sponge rubber, or the like, which may be overlaid with a lining element to prevent direct contact of this pad with the foot, the central heel portion of the shoe being entirely devoid of stitches or other fastening elements.

For a complete understanding of this invention, reference may be had to the accompanying drawings, in which

Figure 1 is a partially disassembled perspective view of certain of the shoe parts, portions being broken away.

Figure 2 is a view partly in side elevation and partly broken away of a shoe embodying the invention.

Figure 3 is a fragmentary elevational view looking rearwardly against the quarter linings and outer-sole and showing a cushion plug in position, certain other parts of the shoe being omitted.

Figure 4 is a fragmentary inverted plan view of the heel portion of the shoe showing the stitch lines.

Referring to the drawings, at 1 is indicated the quarters of the shoe upper which come together substantially centrally of the heel end of the shoe. The quarters are cut away and skived along their edges as at 3 below the top edge of the heel end of the shoe as shown in Figure 3. An outersole member 10 may extend rearwardly in overlapping relation to the lower and forward extremities of the quarters, and about centrally thereof a rounded plug 5 of cushioning material such as sponge or foam rubber is seated to bridge

2

across the lower edges of the quarters and above the rear end portion of the outersole 10 as shown in Figures 2 and 3.

The outersole 10 has a rearward extension 11 which passes around the heel end of the shoe and up outside of the quarters and furnishes an outside backstay portion 12. This outersole thus forms a longitudinally and laterally concave socket at the heel end of the shoe which is overlaid substantially centrally by the plug 5. In engagement with this plug and the top face of the innersole 4 may be placed one or more cushioning elements such as 15 which also may be of sponge or foam rubber, or other suitable material, 15 and overlying the cushion 15 is a short sock lining 16. This sock lining extends up within the quarters at the heel end as shown in Figure 4 and may be secured at its upper edge to the quarters as by stitches 17. This stitching 17 may also pass 20 through the outside backstay portion 12 of the outersole. The forward portions of the sock lining 16 and the cushion element 15 may be cemented into the rounded socket and form therewith a cupped pocket to receive the heel of the 25 wearer, this pocket being concaved both longitudinally and laterally. The lower edges of the quarters may extend between the inner and outersoles where these parts may be secured together as by the lines of stitching 20 shown in Figure 4. These lines of stitching preferably terminate somewhat short of the heel end of the shoe and lines of stitching 21 on opposite sides may secure the side margins of the extension 11 to the quarters. The cushioning element 15 is 30 preferably cemented against the plug 5 and the innersole 4, and the forward end of the sock lining may be cemented to the cushioning element 15 and to the innersole 4.

It will thus be seen that a shoe has been provided in which there is no lateral stitching across 40 the heel pocket and that the side stitching is well spaced from the central portion of the heel pocket and where it is not subjected to the severe pressures which are taken and absorbed by the cushioning elements 15 and 5. The pocket for the heel above the cushioning elements is concave both laterally and longitudinally and provides a socket for the heel of the wearer. This socket is heavily cushioned and is devoid of any fastening elements which might be uncomfortable to the wearer of the shoe, particularly when the wearer subjects the shoe to severe service.

From the foregoing description of an embodiment of this invention, it should be evident to those skilled in the art that various changes and

modifications may be made without departing from its spirit or scope.

I claim:

1. A track shoe having an innersole, an outersole, and upper materials, said outersole extending about the heel portion of the shoe and upwardly toward the top edge of the shoe and outwardly of said upper materials at the heel end, said upper materials having their lower margins extending between said inner and outersoles, lines of stitching spaced from the central axis of the shoe securing said outersole extension to said upper materials, and lines of stitching on opposite sides of the shoe joining said upper materials and inner and outersole adjacent to the side margins of said soles, said outersole and upper materials and innersole forming a longitudinally and laterally concave heel-receiving pocket, a rounded cushioning plug seated and cemented substantially centrally in said pocket, and cushion material and a sock lining overlying said plug and said innersole and upper materials within said pocket.

2. A track shoe having an innersole, an outersole, and upper materials, said outersole extending about the heel portion of the shoe and upwardly toward the top edge of the shoe and outwardly of said upper materials at the heel end, said upper materials having their lower margins extending between said inner and outersoles, lines of stitching spaced from the central axis of the shoe securing said outersole extension to said upper materials, and lines of stitching on oppo-

site sides of the shoe joining said upper materials and inner and outersole adjacent to the side margins of said soles, said outersole and upper materials and innersole forming a longitudinally and laterally concave heel-receiving pocket, a rounded cushioning plug seated and cemented substantially centrally in said pocket, and cushion material and a sock lining overlying said plug and said innersole and upper materials within said pocket, said shoe being devoid of stitches extending laterally of the shoe within the area of said concave pocket.

GEORGE H. GILLIS.
